TURBINE VALVE ACTUATING GEAR

Stephen Jacobs, Lunenburg, and Wayne E. Gleason, Winchendon, Mass., assignors to General Electric Company, a corporation of New York

Application December 26, 1951, Serial No. 263,352

6 Claims. (Cl. 74—110)

This invention relates to elastic fluid turbines particularly to mechanical linkage for connecting a hydraulic actuating motor to multiple inlet valves of a steam turbine.

A commonly used type of inlet valve arrangement for steam turbines includes a plurality of inlet ports arranged in a straight line with separate cooperating valve disc members adapted to seat on each of the ports. The respective discs are provided with actuating stems disposed through a horizontal lift bar with adjustable stop means on the stems so that the discs will be picked up in a desired sequence as the lift bar rises. The lift bar is positioned by two or more vertical tension rods disposed through guide bushings in the valve chest cover plate. Various arrangements have previously been developed for positioning these lift rods by means of a hydraulic motor. Because of the very large forces which must be overcome by the motor, it has been found difficult to provide a simple, compact, and light linkage means for transmitting these large forces without undesirable bending, which might result in inaccurate positioning of the turbine valves and deformation of the linkage parts unless they are made extremely massive.

Accordingly the object of the present invention is to provide an improved linkage mechanism for transmitting force from the hydraulic actuating motor to the lift rods of turbine inlet valves of the type described.

A further object is to provide an improved turbine valve actuating mechanism of the type described in which the hydraulic motor may be conveniently disposed at the side of the turbine valve chest so as to reduce the head-room required for the turbine, while resulting in very little increase in the transverse dimensions thereof. This arrangement has the further important advantage of avoiding the chance that oil leaking from the hydraulic system will fall on the hot valve chest and ignite.

Other objects and advantages will become apparent from the following description taken in connection with the accompanying drawings, in which Fig. 1 is a transverse assembly view, partly in section, of a steam turbine valve chest with a hydraulic valve actuating motor and connecting linkage incorporating the invention, Fig. 2 is a top view of the assembly, and Fig. 3 is an end view, partly in section.

Generally, the invention is practiced by providing a pair of symmetrically disposed torsion tube members having spaced portions connected to the valve lift rods and end portions connected to the hydraulic actuating motor, the torsion members being supported by pivoted links on the valve chest cover plate. The lifting forces applied to the valve actuating rods are transmitted from the hydraulic motor by pure torsion in these tube members, thus eliminating large bending forces.

Referring now more particularly to Fig. 1, the invention is shown as applied to a turbine inlet valve casing 1 defining a valve chamber 2 in which are disposed a plurality of valve discs 3 adapted to seat on the respective inlet ports 4. Each disc has a stem 5 with an adjustable stop member, which may conveniently be in the form of

2

a nut 6 threaded on the rod 5 and secured in desired adjusted position by any suitable locking device. The stems 5 pass freely through the horizontal valve lift bar 7, which is in turn carried on two vertical lift rods 8, 9 slidably disposed in suitable bushings 10, 11 through the valve chest cover plate 12. This cover plate extends transversely to one side of the valve chest, the projecting portion 12a forming the support for the hydraulic motor shown generally at 13.

10 Motor 13 may be of any suitable type, but is shown here as comprising a single-acting piston 13a biased downwardly by a heavy coil spring 13b and adapted to be positioned upwardly by hydraulic operating liquid admitted to the piston by suitable pilot valve means contained in the housing 14. The details of the pilot mechanism are not necessary to an understanding of the present invention, and are, therefore, not described in more detail.

The type of valve arrangement shown will be familiar to those acquainted with the turbine art. Vertical movement of the lift bar 7 picks up the respective stems 5 in a preselected sequence as determined by adjustment of the stops 6. It will be apparent that the lift rods 8 and 9 are constrained to move in a vertical plane by the guide bushings 10, 11. Because of the comparatively small diameter of these rods 8, 9, which are intended to be stressed principally in tension, it is important that there be no substantial transverse forces applied thereto by the valve actuating linkage.

30 The hydraulic motor 13 may conveniently be secured to the projecting portion 12a of the valve chest cover plate by means of an axially extending attachment flange portion 13c which is disposed through a U-shaped cutout 12b in the end of cover plate portion 12a, and has an end flange portion 13d secured by a plurality of suitable threaded fastenings 13e to the top surface of frame portion 12a. It will be seen that the valve chest cover plate 12 and the transversely extending portion 12a are of substantial thickness and well able to take any forces imposed by the weight and action of the hydraulic motor. 40 Thus the cover plate 12 becomes the main frame member for the valve gear. Actually, with a force-transmitting linkage in accordance with the invention, only very small forces are imposed on the frame plate 12.

45 The force-transmitting linkage to which this invention particularly relates comprises a pair of torque tubes 14a, 14b disposed above the frame plate 12 in parallel relation with the valve lift bar 7. An intermediate and one end portion of these torque tubes are connected to the valve lift rods 8, 9 respectively, while the other end portions of the tubes are connected to the piston rod 13f of the hydraulic motor. The pivoted link means by which these connections are effected will be apparent from a comparison of Figs. 1, 2, and 3.

50 As perhaps appears most clearly in Fig. 3, each tube is penetrated by a plurality of rod members identified 15a, 15b, etc. These rod members may conveniently be disposed through drilled holes in the torque tubes and are secured thereto, as by welding. The outer end of each rod is provided with a vertical slot shown at 16 in Figs. 1 and 2, which slot provides a bifurcated end portion which is pivoted to the upper end of the supporting links 18a, 18b, etc. It will be apparent from Fig. 3 that each link 18 is pivotably received in a fitting 19 suitably secured, as for instance, by threaded fastenings 20, to the frame plate 12.

55 The inner ends of the respective rods 15 are cut away at opposite sides thereof to form a projecting flat end portion identified 21a, 21b, etc. These flat end portions are disposed at either side of, and pivotably connected to, the respective end fittings 22a, 22b, and 22c, of the lift rods 9, 8, and hydraulic motor piston rod 13f.

60 70 As seen in Fig. 3, the pivots connecting support links

18 with the fulcrum members 19 are identified 23a, 23b, etc. The pivots connecting the upper ends of support links 18 with the outer ends of the respective rods 15 are identified 24a, 24b, 24c, 24d, 24e, 24f. The third set of pivots connecting the inner ends of rods 15 with the valve lift rods and piston rod are identified 25a, 25b, 25c, respectively.

The operation of the connecting linkage is as follows: When the valve discs 3 are in closed position, the lift bar 7 is, of course, at its lowermost position and piston 13a is biased to its extreme lowermost position by spring 13b. When hydraulic operating liquid is supplied to the motor 13, piston 13a moves upwardly against the bias of spring 13b so that the piston rod fitting 22c pushes upwardly on the rod end portions 21e, 21f (Fig. 2). Since the load is represented by a downward force on the lift rods 8, 9, the upward thrust of the hydraulic motor loads the tubes 14a, 14b in pure torsion. It will be observed that these tubes are of comparatively large diameter so that they are well able to take these torsion forces. It is also important to note that the symmetrical arrangement of the two parallel torque tubes insures that these forces will be equally distributed so that there will be no transverse forces imposed by piston rod 13f on the valve lift rods 8, 9.

As will be most readily apparent from Fig. 3, upward motion of the pivots 25a, 25b, 25c will be in a vertical plane by reason of the vertical guiding effect of the bushings 10, 11 and the guide bushing 13g of the hydraulic motor. It will also be apparent that the resulting rotational movement of the rods 15a, 15b, etc., about their respective pivots 24, will mean that the torque tubes 14a, 14b will be displaced slightly toward and away from each other; and this transverse shifting is permitted by the pivoted support links 18.

It will be apparent to those skilled in the mechanical arts that the use of two parallel symmetrically disposed torque tubes permits the transmission of enormous forces from the hydraulic motor to the valve gear without the introduction of any serious bending forces tending to deform the actuating linkage and without imposing any transverse forces on the valve lift rods or piston rod, since the force is transmitted as pure compression in the piston rod, pure tension in the valve lift rods, and pure torsion in the tubes 14.

It will be seen that the invention provides an extremely compact and rugged valve actuating linkage which permits placing the hydraulic motor closely adjacent the valve chest and at one side thereof, as contrasted with prior art arrangements requiring the motor to be disposed above or below the valve chest. The simplicity of the parts constituting the force-transmitting linkage, makes the mechanism substantially foolproof. All parts are, of course, readily accessible for inspection and lubrication.

It will be obvious that many changes and substitutions of equivalents may be made without departing from the spirit of the invention. For instance, while a hollow cylinder is the most efficient torque-transmitting member, for a given size and weight, it is possible to make the members 14a, 14b of other geometric shapes. Also other arrangements for pivotally supporting the torque members could be substituted for the simple links 18. The arrangement is obviously applicable to turbines having other types of inlet valves and other types and arrangements of hydraulic motor for positioning the valves. It is, of course, intended to cover by the appended claims all such modifications as fall within the true spirit and scope of the invention.

What I claim as new and desire to secure by Letters Patent of the United States is:

1. In actuating linkage for transmitting force from an actuating motor with a linearly reciprocating member to at least two spaced actuated members linearly reciprocable in the same plane as the motor actuating mem-

70
75

ber, the combination of a frame plate member disposed in a plane normal to the reciprocable members, bushing members secured relative to said frame plate member and adapted to constrain at least two of said three reciprocable members to move in a plane normal to the frame plate member, a pair of separate axially elongated torque members disposed parallel to the frame plate member at opposite sides of the free ends of said three reciprocable members, pivot means connecting said free ends of the three reciprocable members to the respective adjacent side portions of the torque members, and at least two support link means connected to each of said torque member, each link means having one end portion pivotally secured to the frame plate member and the other end portion pivotally connected to the respective torque members at the sides thereof remote from said first mentioned pivot means, whereby linear motion of the actuating motor member effects rotational displacement of the torque members to cause the actuated members to move linearly relative to the support bushings.

2. In actuating linkage for transmitting force from motor means having a linearly reciprocable actuating member to an actuated member disposed for reciprocating movement parallel to the actuating member, the combination of a frame member disposed substantially in a plane normal to the reciprocable members, bushing members secured relative to the frame member and adapted to constrain the reciprocable members to move in a plane substantially normal to the frame member, a pair of separate axially elongated torque members disposed parallel to the frame at opposite sides of the respective ends of the reciprocable members, first pivot means connecting the ends of the reciprocable members to the respective adjacent side portions of the torque members, and a plurality of support link means connected to each torque member, each link means having one end portion pivotally secured to the frame member and the other end portion pivotally connected to one of the torque members at the side thereof remote from said first pivot means, whereby linear movement of the actuating motor member effects rotational displacement of the torque members about the supporting link means to cause the actuated member to move linearly in its bushing.

3. Turbine valve actuating gear comprising a frame plate secured to a turbine inlet valve casing and having at least two reciprocable valve positioning rod members adapted to slide in bushing members disposed through said frame plate whereby the rod members are constrained to move linearly in a plane substantially normal to the frame plate, actuating motor means secured to the frame plate and having a reciprocable actuating member disposed in the same plane as and transversely spaced from the rod members, said actuating member having an end portion aligned with the respective outer ends of said rod members, a pair of separate axially elongated torque members disposed parallel to the frame plate at opposite sides of the ends of said valve rod members and said actuating member respectively, pivot means connecting the ends of said three reciprocable members to the respective adjacent side portions of the torque members, and a plurality of support link means connected to each of said torque member, each link means having one end portion pivotally connected to the frame plate and the other end portion pivotally connected to one of the torque members at the side thereof remote from said first-mentioned pivot means, whereby linear motion of the actuating member effects rotational displacement of the torque members to cause the valve rod members to move linearly in their bushings.

4. In a mechanical actuator, the combination of a motor having a reciprocable actuating member, a reciprocable actuated member, a frame with guide means adapted to constrain said reciprocable members to move in parallel paths substantially normal to the frame, a pair of separate axially elongated parallel torque members dis-

posed longitudinally of the frame at opposite sides of the reciprocable members, first pivot means connecting the reciprocable members to respective adjacent side portions of the torque members, and at least two longitudinally spaced support link means connected to each torque member, each of said link means having one end portion pivotally secured to the frame with the other end portion pivotally connected to a torque member at the side thereof remote from said first pivot means, whereby linear motion of the actuating member effects rotational displacement of the torque members about the support link means to cause the actuated member to move linearly relative to its guide means.

5. Actuating mechanism in accordance with claim 4 in which the torque members are tubes with longitudinally spaced parallel rod members projecting diametrically through and secured to the tubes, each rod having one projecting end portion pivoted to one of the reciprocable members and the other projecting end portion pivoted to one of the support link means.

6. In a mechanical actuator, the combination of motor means having a linearly reciprocable actuating member, an actuated member disposed for reciprocating movement

parallel to the actuating member, a frame member disposed substantially in a plane normal to the reciprocable members, guide means secured relative to the frame member and adapted to constrain the reciprocable members to move in parallel paths, a pair of separate axially elongated parallel torque members disposed parallel to the frame member at opposite sides of the reciprocable members, pivot means connecting the respective reciprocable members to longitudinally spaced side portions of the torque members, and means rotatably supporting the torque members relative to the frame member, whereby linear movement of the actuating motor member effects rotational displacement of the torque members in opposite directions of rotation to cause the actuated member to move linearly relative to its guide means.
